TRAVELING WAVE ELECTRON DISCHARGE DEVICE

Theodore J. Marchese, Nutley, N.J., assignor to International Telephone and Telegraph Corporation, Nutley, N.J., a corporation of Maryland

Application January 6, 1958, Serial No. 707,211

16 Claims. (Cl. 315—3.6)

This invention relates to traveling wave electron discharge devices and more particularly to slow wave propagating structures employed in relatively high power traveling wave electron discharge devices.

The usual slow wave propagating structure employed in traveling wave tubes to reduce the phase velocity of wave energy to approximately the phase velocity of the electron beam is a helical-type transmission line. This helical-type slow wave structure enables the successful amplification of wave energy by synchronous interchange of energy between the electron beam and the wave energy. However, it is now well known that the power handling capabilities of a helix are limited since an attempt to increase the power output of a helix traveling wave tube results in increased heating of the helical propagating structure due to resistive losses and, hence, an increase in impedance of the helical propagating structure. This increased impedance of the helical propagating structure reduces the gain of the device and hence places a limit on the possible power output from this type traveling wave tube. Due to the limited power handling capabilities, the helical propagating structure has become known as a relatively low power slow wave propagating structure.

Since it is desirable to obtain power output of a traveling wave tube well beyond the efficient power output possible with a helical-type traveling wave tube, loaded waveguide transmission lines are now being employed as the slow wave propagating structure for high power traveling wave tubes since these transmission lines have relatively high power handling capabilities. Although this type of slow wave propagating structure is a solution to obtain increased power output over that obtainable with a helical-type structure it is necessary to increase the length and diameter of the tube structure since the gain per unit length of a loaded waveguide is less than the gain per unit length of a helix, and the loaded waveguide is inherently greater in diameter. The increased length and diameter of the resultant prior art high power traveling wave tube are objectionable because of increase tube size and longer and larger magnetic structures for beam focusing in the region of the slow wave propagating structure. In addition manufacture of a loaded waveguide slow wave propagating structure is expensive relative to a helical type structure.

Therefore, it is an object of this invention to provide an improved high power slow wave propagating structure for use in a traveling wave tube.

Another object of this invention is to provide a slow wave propagating structure of relatively high power handling capabilities having decreased manufacturing cost.

Still another object of this invention is to provide a slow wave propagating structure for a traveling wave tube which has a power handling capability substantially the same as a loaded waveguide slow wave propagating structure but which is shorter in length and lighter than the loaded waveguide structure.

2

A feature of this invention is the provision of a composite slow wave propagating structure comprising a slow wave transmission line of relatively low power handling capabilities, such as a helical transmission line, a slow wave transmission line of relatively high power handling capabilities, such as a loaded waveguide transmission line, and means to couple the wave energy between said low power transmission line and said high power transmission line.

10 Another feature of this invention is to dispose the wave energy attenuation adjacent the area where wave energy is coupled from one component to the other component of the composite slow wave propagating structure.

15 Another feature of this invention is to dispose the wave energy attenuation solely adjacent the low power transmission line in juxtaposition to the output end thereof and to extend a portion of the low power transmission line into the high power transmission line for excitation thereof with energy on said low power transmission line.

20 A further feature of this invention is to dispose the signal wave attenuation material at the output of the low power transmission line and at the input of the high power transmission line and to couple energy from the low power transmission line to the high power transmission line by means of the electron beam which is in interacting relation with the composite slow wave propagating structure.

25 Still a further feature of this invention is the provision of a counterwound helix as the low power transmission line and an iris-loaded waveguide as the high power transmission line.

30 The above-mentioned and other objects and features 35 of this invention will become more apparent by reference to the following description taken in conjunction with the accompanying drawings, in which:

35 Fig. 1 is a schematic cross-sectional view of a traveling wave tube employing one form of a composite slow wave propagating structure in accordance with the principles of this invention; and

40 Fig. 2 is a schematic cross-sectional view of a traveling wave tube employing still another form of a composite slow wave propagating structure in accordance with the principles of this invention.

45 Referring to Fig. 1, a traveling wave tube is illustrated as including therein one form of slow wave propagating structure following the principles of this invention. The tube includes a vacuum envelope 1 composed of metal, 50 a collector electrode 2 disposed at one end of envelope 1 and an electron gun 3 disposed at the other end of envelope 1 for projecting an electron beam along a given path 4 to collector electrode 2. A magnetic focusing arrangement 5 is disposed coaxial of path 4 to maintain the electrons of the beam focused throughout its travel from gun 3 to electrode 2. Arrangement 5 is illustrated as an electromagnet, but it is to be understood that a permanent magnet may be substituted therefor.

55 A composite slow propagating structure 6 is disposed 60 in juxtaposition to path 4 to enable interaction between the electron beam flowing along path 4 and the wave energy propagated on structure 6 at substantially the same phase velocity as the electrons of the electron beam. In accordance with this invention, composite structure 65 6 includes a low power slow wave transmission line illustrated as being a helical-type transmission line 7 and a high power slow wave transmission line illustrated as being an iris-loaded waveguide transmission line 8. It is to be understood that any loaded waveguide will be suitable as the high power portion of the composite slow wave structure 6. It is to be further understood that the electron beam may be an annular beam to be in

interacting relation with the wave energy on a loaded waveguide, such as a disc-loaded waveguide. Helical transmission line may be supported by dielectric rods 9 which are positioned at one end thereof by member 10 disposed transversely of envelope 1 having mounted thereon ring 11 for engaging the ends of rods 9. The other end of the rods 9 are positioned by ring 12 secured to element 13 forming one of the iris loading elements of transmission line 8.

Radio frequency wave energy to be amplified is coupled by means of input terminal 14 to the end of helical line 7 adjacent electron gun 3. The wave energy is then propagated down helical line 7 for interaction with the electrons of the electron beam. The wave propagated on helical line 7 is composed of three components, a steady state wave, a decreasing wave, and an increasing wave. Attenuation section 15 is disposed adjacent the output end of helical line 7 to effect a suppression of the steady state and decreasing waves but primarily it serves to absorb any waves reflected back toward the input. Helical line 7 is preferred to be of the counterwound type to help in suppressing the backward wave. After the forward wave passes attenuation section 15, the wave energy is amplified by portion 16 of helical line 7 prior to coupling to loaded waveguide 8 through an arrangement to excite loaded waveguide 8, such as probe coupling 17. Hence, loaded waveguide 8 is excited by the wave energy on helical line 7 wherein the wave energy is increased to a relatively high power. The relatively high power is coupled from loaded waveguide 8 by means of wave energy output terminal means 18.

Hence, by employing the composite slow wave structure 6 of this invention, the wave energy is amplified in helical line 7 to a value substantially equal to the limiting value of a helical structure in a shorter length than could be accomplished by a loaded waveguide structure. The output of helical line 7 is then coupled to waveguide 8 wherein the power of the wave energy at the output of helical line 7 is increased in power to a relatively high power output. The value of output power of the composite propagating structure is comparable in value to that of an all loaded waveguide structure, but resulting in a short overall length since the helical structure has a higher gain per unit length than that of the loaded waveguide structure.

Referring now to Fig. 2, another form of composite slow wave propagating structure 6 is illustrated. The difference between structure 6 of Fig. 1 and structure 6 of Fig. 2 is the means for coupling wave energy between the low and high power transmission line sections. Therefore, the reference characters employed in Fig. 1 will be employed for like components in Fig. 2 and only the differences between the two embodiments will be discussed hereinbelow with reference to Fig. 2.

Envelope 1 of the embodiment of Fig. 2 may be composed of metal as illustrated in Fig. 1 or the envelopes may be constructed as shown in Fig. 2 including a metallic portion 19 in the vicinity of loaded waveguide 8 and dielectric portions 20 to complete the vacuum envelope substantially as shown. It is to be understood, however, that the vacuum envelope may be completely dielectric with the loaded waveguide disposed therein.

As mentioned hereinabove, the only difference between the composite slow wave structures of Figs. 1 and 2 is in the means coupling the energy from helical line 7 to loaded waveguide 8. In the embodiment of Fig. 2, the wave energy is coupled from helical line 7 to loaded waveguide 8 by the electron beam of the device. As is known, this can be done since the electron beam is density modulated by wave energy on helical line 7 and this density modulation of the electron beam will excite loaded waveguide 8. The output section of helical line 7 is terminated in attenuating material 21 at the end thereof and the input of loaded waveguide 8 is terminated in attenuating material 22 coated on portion of the inner

walls of the first section thereof to absorb any waves reflected from the output load.

While I have described above the principles of my invention in connection with specific apparatus, it is to be clearly understood that this description is made only by way of example and not as a limitation of the scope of my invention as set forth in the objects thereof and in the accompanying claims.

I claim:

1. In a traveling wave electron discharge device of the type wherein interaction takes place between the electrons of an electron beam and wave energy propagated on a slow wave propagating structure disposed in juxtaposition with said electron beam, a slow wave propagating structure having an energy wave input terminal and an energy wave output terminal comprising a helical-type transmission line coupled to said input terminal, a loaded waveguide-type transmission line coupled to said output terminal and means to couple wave energy between said helical transmission line and said waveguide transmission line.
2. In a traveling wave electron discharge device of the type wherein interaction takes place between the electrons of an electron beam and wave energy propagated on a slow wave propagating structure disposed in juxtaposition with said electron beam, a slow wave propagating structure having an energy wave input terminal and an energy wave output terminal comprising a helical-type transmission line having one end thereof coupled to said input terminal, a loaded waveguide-type transmission line having one end thereof coupled to said output terminal, wave energy attenuating means disposed adjacent the point where the other end of said helical transmission line is in juxtaposition with the other end of said waveguide transmission line and means coupling wave energy between said helical transmission line and said waveguide transmission line.
3. The structure according to claim 2, wherein said attenuating means is disposed adjacent said other end of said helical transmission line.
4. The structure according to claim 3, wherein said coupling means includes a portion of said helical transmission line extending into said waveguide transmission line for excitation thereof with wave energy on said helical transmission line.
5. The structure according to claim 2, wherein said attenuating means is disposed at said other end of said helical transmission line and at said other end of said waveguide transmission line.
6. The structure according to claim 5, wherein said coupling means includes said electron beam.
7. In a traveling wave electron discharge device of the type wherein interaction takes place between the electrons of an electron beam and wave energy propagated on a slow wave propagating structure disposed in juxtaposition with said electron beam, a slow wave propagating structure having an energy wave input terminal and an energy wave output terminal comprising a counterwound helical transmission line having one end thereof coupled to said input terminal, an iris-loaded waveguide transmission line having one end thereof coupled to said output terminal, wave energy attenuating means disposed adjacent the point where the other end of said helical transmission line is in juxtaposition with the other end of said waveguide transmission line and means coupling wave energy between said helical transmission line and said waveguide transmission line.
8. The structure according to claim 7, wherein said attenuating means is disposed adjacent said other end of said helical transmission line and said coupling means includes a portion of said helical transmission line extending into the adjacent section of said waveguide transmission line for excitation thereof with the wave energy on said helical transmission line.
9. The structure according to claim 7, wherein said

attenuating means is disposed at said other end of said helical transmission line and in the first section at said other end of said waveguide transmission line and said coupling means includes said electron beam.

10. A composite slow wave propagating structure for wave energy comprising a helical-type transmission line, a wave energy input means coupled to one end of said helical transmission line, a loaded waveguide-type transmission line, a wave energy output means coupled to one end of said waveguide transmission line, and means to couple wave energy between the other end of said helical transmission line and the other end of said waveguide transmission line.

11. A composite slow wave propagating structure for wave energy comprising a counterwound helical transmission line, a wave energy input means coupled to one end of said helical transmission line, an iris-loaded waveguide transmission line, a wave energy output means coupled to one end of said waveguide transmission line, and means to couple wave energy between the other end of said helical transmission line and the other end of said waveguide transmission line.

12. A traveling wave electron discharge device comprising a vacuum envelope, a collector electrode disposed adjacent one end of said envelope, a means to project an electron beam along a given path toward said collector electrode disposed adjacent the other end of said envelope, a wave energy propagating structure disposed in interacting relation with the electrons of said electron beam including a helical-type transmission line extending along said path from a point adjacent said electron beam projecting means to a point intermediate said electron beam projecting means and said collector electrode, a loaded waveguide-type transmission line extending along said path from a point adjacent said intermediate point to a point adjacent said collector electrode, wave energy attenuating means disposed adjacent said intermediate point, and means to couple wave energy between said helical transmission line and said waveguide transmission line, input wave energy terminal means in coupled relation with said helical transmission line adjacent said electron beam projecting means, and output wave energy terminal means in coupled relation with said waveguide transmission line adjacent said collector electrode.

13. A discharge device according to claim 12, wherein said attenuating means is disposed in juxtaposition with said helical transmission line adjacent said intermediate point and said coupling means includes a portion of said helical transmission line extending into said waveguide transmission line for excitation thereof with the wave energy on said helical transmission line.

14. A discharge device according to claim 13, wherein said attenuating means is disposed in juxtaposition with said helical transmission line and said waveguide transmission line immediately adjacent said intermediate point and said coupling means includes said electron beam.

15. A traveling wave electron discharge device comprising a vacuum envelope, a collector electrode disposed

adjacent one end of said envelope, a means to project an electron beam along a given path toward said collector electrode disposed adjacent the other end of said envelope, a wave energy propagating structure disposed in interacting relation with the electrons of said electron beam including a counterwound helical transmission line extending along said path from a point adjacent said electron beam projecting means to a point intermediate said electron beam projecting means and said collector electrode, an iris-loaded waveguide transmission line extending along said path from a point adjacent said intermediate point to a point adjacent said collector electrode, wave energy attenuating means disposed in juxtaposition with said helical transmission line adjacent said intermediate point and a portion of said helical transmission line extending into said waveguide transmission line for excitation thereof with wave energy on said helical transmission line, input wave energy terminal means in coupled relation with said helical transmission line adjacent said intermediate point and said portion of said helical transmission line, output wave energy terminal means in coupled relation with said waveguide transmission line adjacent said collector electrode.

16. A traveling wave electron discharge device comprising a vacuum envelope, a collector electrode disposed adjacent one end of said envelope, a means to project an electron beam along a given path toward said collector electrode disposed adjacent the other end of said envelope, a wave energy propagating structure disposed in interacting relation with the electrons of said electron beam including a counterwound helical transmission line extending along said path from a point adjacent said electron beam projecting means to a point intermediate said electron beam projecting means and said collector electrode, an iris-loaded waveguide transmission line extending along said path from a point adjacent said intermediate point to a point adjacent said collector electrode, wave energy attenuating means disposed in juxtaposition with said helical transmission line and said waveguide transmission line immediately adjacent said intermediate point, and said electron beam coupling wave energy between said helical transmission line and said waveguide transmission line, input wave energy terminal means in coupled relation with said helical transmission line adjacent said electron beam projecting means, and output wave energy terminal means in coupled relation with said waveguide transmission line adjacent said collector electrode.
